UNITED STATES PATENT OFFICE

157,874

PAIR OF TONGS

James O. Kolden, Amherst Junction, Wis.

Application June 4, 1948, Serial No. 146,761

Term of patent 7 years

(Cl. D44—4)

To all whom it may concern:

Be it known that I, James O. Kolden, a citizen of the United States, residing at Amherst Junction, in the county of Portage, and State of Wisconsin, have invented a new, original, and ornamental Design for a pair of Tongs, of which the following is a specification, reference being had to the accompanying drawing, forming part thereof.

Figure 1 is a perspective view of a pair of tongs in an open position, showing my new design,

Figure 2 is a side elevational view thereof in a closed position, and

Figure 3 is a front end view of the subject shown in Figure 2.

I claim:

The ornamental design for a pair of tongs, as shown.

JAMES O. KOLDEN.
